CLAIM

The ornamental design for an electronics case, as shown and described.

DESCRIPTION

FIG. 1 is a perspective view of an electronics case showing my design;

FIG. 2 is a bottom plan view thereof;

FIG. 3 is a front plan view thereof; the rear plan view being a mirror image thereto; and,

FIG. 4 is a left side plan view thereof; the right side plan view is a mirror image thereto.

The broken lines showing of the ventilation holes, foot pads and outer edge shown in the drawings illustrate the portion of the design that form no part of the claimed design.
